UNITED STATES PATENT OFFICE.

ALFRED F. McCOLLUM, OF BLOOMSBURG, PENNSYLVANIA, ASSIGNOR OF THREE-FIFTHS
TO JAMES MAGEE, 2D, OF BLOOMSBURG, PENNSYLVANIA.

SHUTTLE.

1,238,542.

Specification of Letters Patent. Patented Aug. 28, 1917.

Application filed June 28, 1916. Serial No. 106,420.

To all whom it may concern:

Be it known that I, ALFRED F. McCOLLUM, a citizen of the United States, residing in Bloomsburg, Columbia county, Pennsylvania, have invented a Shuttle, of which the following is a specification.

One object of this invention is to provide a novel form of shuttle, particularly of the type used in webbing or ribbon looms, whose 10 construction shall be such as to effectually prevent the heavy pull on or breakage of the yarn in case it slips off of either end of the bobbin; the invention contemplating a construction especially designed to facilitate 15 the insertion and removal of said bobbin from the shuttle.

Another object of the invention is to provide a shuttle with a novel form of bearings which shall be so proportioned that the 20 bobbin is free to slide longitudinally in opposite directions and by reason of this action, alternately disengage its supporting spindles as the yarn unwinds, thereby permitting the free delivery of said yarn in case 25 it should become so loosened as to allow one or more turns to come off over the end of the bobbin.

I further desire to provide a shuttle of the 30 type noted with a novel form of bobbin-supporting means including a spindle and an open bearing for each end of the same, together with a novel construction and arrangement of parts for permitting of the rapid threading of said shuttle.

These objects and other advantageous ends 35 I secure as hereinafter set forth, reference being had to the accompanying drawings, in which:

Figure 1 is a side elevation of a shuttle 40 constructed according to my invention;

Fig. 2 is a vertical section on the line 2-2, Fig. 1;

Fig. 3 is a plan of a part of the top of the 45 shuttle frame showing it as equipped with my quick threading device; and

Fig. 4 is a perspective view of the bushing or eyelet for guiding the yarn as it passes from the bobbin.

In the above drawings 1 represents the 50 wooden frame or body of a shuttle which in plan is of a substantially semi-elliptic outline, having an elongated opening in which the bobbin x is rotatably mounted. The base member of the frame is formed 55 with the customary elongated guideway 2

on one side and with a toothed rack 3 at the opposite side, there being also a porcelain or glass eyelet or opening 4 forming a yarn guide and set in the central portion of the top member of said frame.

As shown in Fig. 3 this eyelet is made in the form of a flattened ring 11' having an inclined cut or passageway in one side, and the adjacent part of the shuttle frame likewise has through it an inclined cut or slot 12 registering with and forming a continuation of the cut 13 in said eyelet. Mounted in a shallow slot or depression to one side of the eyelet 4 and extending longitudinally of the frame across the upper end of the slot 12 is a spring keeper in the form of a resilient wire 14 fixedly held to the frame 1 at 60 one end and free at the opposite end.

The bearings for the support of the bobbin x consist of two cylindrical cuplike structures 5 and 6 made of sheet metal and more or less yieldingly supported by a strip metal piece 7 extending between them but rigidly held to the base member of the shuttle by screws as shown. Each of these bearing shells is cut away at one side to permit of the easy introduction of the bobbin x and they are such a distance apart that when one end of the bobbin is in engagement with the end of the bearing 6 for example, the opposite end of said bobbin extends a short distance within the second shell 5. The bearings have relatively short tapered spindles or pintles 8 and 8^a projecting toward each other from their ends and their lengths are 75 such that when the bobbin lies fully within one of the bearings, against the end thereof, its opposite end is spaced some distance away from the pointed end of the spindle in the other bearing, although it is rotatably 80 carried by the latter bearing structure.

Any suitable braking or retarding device 85 may be used on the bobbin and this in the present instance also assists in holding said bobbin in its bearings. In the case illustrated said device consists of a rod 9 extending across the opening in the shuttle adjacent one side of the base and carrying a plate 10 yieldingly engaging the yarn at about the middle part of the bobbin, under 100 the action of a spring 11 coiled on the rod 9 and acting upon said plate.

Under conditions of use as the yarn x' is drawn out of the shuttle and unwinds from the left hand side of the bobbin for exam- 110

ple, the pull of said yarn causes said bobbin to move to the right so that the right hand spindle or pivot 8 enters its central longitudinal passage and rotatably supports its 5 right hand end, holding it from engaging the bearing shell 6. If while the yarn is being delivered, one or more of its coils adjacent the left hand end should become loosened and slip off over the same, no increase in the tension of said yarn would result nor would there be any tangling, since there is a space between the end of the bobbin and the spindle 8^a through which such coils could freely pass. When the yarn so 10 far unwinds from the bobbin as to pass the middle thereof and begin to feed from the right hand end, its tension causes the bobbin to move longitudinally to the left so that its left hand end is rotatably carried on the 15 spindle 8^a while its right hand end is rotatably supported by the bearing 6, some distance away from the spindle 8, with the same advantages as noted in connection with the spindle 8^a.

20 Obviously the bobbin may be removed with the utmost ease and in a minimum time, since for this purpose it is merely necessary to raise the plate 10 and after lifting the bobbin out of one of its bearings 25 5 or 6, to slide it off of the short spindle 8 or 8^a. A filled bobbin may likewise be placed in the shuttle with the greatest convenience since after the plate 10 has been drawn out, one end of said bobbin may be 30 placed in one of the bearings 5 or 6 with the spindle thereof projecting into its central passage, after which the opposite end 35 may be dropped into the other bearing and the plate 10 released. The yarn is then 40 pressed into the slot 12 and, while the bobbin is held, drawn against the retaining keeper 14, which is thereupon raised to permit 45 said yarn to pass under it into the eyelet 4. Obviously said keeper effectually serves to prevent escape of the yarn from the eyelet, although it may be omitted without departing from my invention, in which case the overhanging ends of the eyelet are depended on to perform the same function.

50 As a result of the use of my construction the speed of operation and capacity of the loom are increased, especially since there is no time lost by the possible dropping of the long spindle which has heretofore been used to rotatably support the bobbin in 55 shuttles of the class illustrated. Moreover by means of the peculiarly formed eyelet 4 and its associated parts, an additional time is saved in threading the shuttle.

60 Another important advantage of my invention arises from the decreased number of breakages of the yarn and the lessened time during which the loom is out of service, for by permitting the loosened coils of the yarn 65 to freely pull away from the bobbin instead

of wrapping around a spindle, there is practically constant tension on said yarn with no tendency to break the same.

I claim:

1. The combination in a shuttle of a frame; and two bearings carried thereby in positions to rotatably support a bobbin while permitting longitudinal movement thereof in the frame; with means for rotatably supporting the bobbin in the shuttle independently of said bearings. 70

2. The combination in a shuttle of a frame; and two cup-shaped bobbin-receiving bearings each open at one side of said frame to permit of the removal of the bobbin and spaced with their ends a greater distance apart than the length of the bobbin; with means for rotatably supporting either end of the bobbin in the shuttle independently of said bearings. 80

3. The combination in a shuttle of a frame; two bearings mounted therein in positions to rotatably support a bobbin and spaced to permit movement of said bobbin longitudinally of the frame; with short spindles in the bearings respectively in positions to rotatably support the bobbin. 90

4. The combination in a shuttle of a frame; two bearings mounted therein in positions to rotatably support a bobbin and spaced to permit movement of said bobbin longitudinally of the frame; with short spindles in the bearings respectively in positions to rotatably support the bobbin, the length of the bobbin plus the length of either spindle being less than the distance between the ends of the bearings. 95

5. The combination in a shuttle of a frame; two open sided bearings therein; and spindles for the bearings; the distance between the ends of the bearings being greater than the length of a bobbin and the distance between the end of either bearing and the adjacent edge of the other bearing being less than the length of the bobbin. 105

6. The combination in a shuttle of a frame having an opening and provided with a yarn guide leading therefrom; cup shaped bearings mounted at opposite ends of the opening with their ends at a greater distance apart than the length of the bobbin used in the shuttle; and relatively short spindles mounted in the bearings respectively in positions to enter and support the ends of said bobbin as this is alternately moved in opposite directions in the bearings by the pull of the yarn passing through the yarn guide. 115

7. The combination in a shuttle of a frame; two cup-shaped bobbin bearings therein each open on one side of the frame; with a spring-pressed plate mounted between the bearings to retain the bobbin therein; and means for supporting either end of the bobbin independently of said bearing. 125

8. The combination in a shuttle of a frame; 130

two relatively short spindles mounted therein, and spaced such a distance apart that either of them is free of the bobbin when the latter is engaged as far as possible with the other spindle; and means for rotatably supporting that end of the bobbin which is disengaged from its spindle.

9. The combination in a shuttle of a frame; two relatively short spindles mounted therein, and spaced such a distance apart that either of them is free of the bobbin when it is engaged as far as possible with the other spindle; means for rotatably supporting that end of the bobbin which is disengaged from its spindle; and means for yieldingly holding the bobbin in place.

10. The combination in a shuttle of a frame; two bobbin bearings mounted therein with their ends at a materially greater distance apart than the length of a bobbin in order to permit the latter to move longitudinally therein; with means for rotatably supporting either end of the bobbin out of engagement with its adjacent bearing when

25 it is moved into the same a predetermined distance.

11. The combination in a shuttle of two bearings; and relatively short tapering spindles in said bearings respectively, the distance from the end of either one of the bearings to the end of the spindle in the other bearing being greater than the length of the bobbin, the diameter of the bearings being greater than that of the bobbin ends so that

either end of said bobbin is supported independently of its bearing when it rotatably engages the spindle therein.

12. The combination in a shuttle of a frame having an opening and a yarn guide leading therefrom; a support of spring material mounted in the opening; two open sided bearings carried by said support with their ends at a greater distance apart than the length of a bobbin; and pointed spindles for the bearings, one spindle being clear of a bobbin when the latter is on the other spindle with its end engaging the end of the adjacent bearing.

13. The combination in a shuttle of a frame having an opening and a yarn guide leading therefrom; two open sided bearings carried by said frame; and pointed spindles for the bearings, the distance from the end of one bearing to the point of the spindle in the other bearing being greater than the length of a bobbin for use in said shuttle.

14. The combination in a shuttle of a frame; and means for supporting a bobbin in the frame with that end from which yarn is being delivered, supported to permit the free drawing over it of any coils of the yarn which come off of said bobbin; and spindles mounted to alternately engage and support the non-delivery end of the bobbin as said bobbin is alternately moved in opposite directions longitudinally of the frame under the action of the yarn.
